UNITED STATES PATENT OFFICE.

EUGENE F. DAVENPORT, OF MELROSE, MASSACHUSETTS, ASSIGNOR TO UNITED SHOE MACHINERY COMPANY, OF PATERSON, NEW JERSEY, A CORPORATION OF NEW JERSEY.

VAMP-MARKING MACHINE.

968,746.

Specification of Letters Patent. Patented Aug. 30, 1910.

Application filed September 28, 1907. Serial No. 395,000.

To all whom it may concern:

Be it known that I, EUGENE F. DAVENPORT, a citizen of the United States, residing at Melrose, in the county of Middlesex and 5 Commonwealth of Massachusetts, have invented certain Improvements in Vamp-Marking Machines, of which the following description, in connection with the accompanying drawings, is a specification, like 10 reference characters on the drawings indicating like parts in the several figures.

This invention relates to machines for marking shoe vamps with various marks of assistance to the operator in assembling the 15 parts of the shoe and comprises improvements in machines of the above class by which they are adapted to mark that form of vamp commonly known as bluchers or other fancy or unusual forms of vamps. 20 These vamps are, as a rule, not adapted to be accurately positioned by the guides heretofore employed in vamp marking machines and one feature of my invention relates to the provision of means for accurately determining 25 the correct position of a vamp of the above nature and holding it in such position while it is being acted upon by the various marking agencies. Preferably the marking means and vamp positioning means are so 30 constructed and arranged that one may be moved relatively to the other to adapt the machine to mark either right or left vamps, and the vamp positioning means are adjustable to accommodate different length vamps. 35

Another feature of the invention relates to the provision of means for indicating on a vamp the proper overlap for the quarters or foxing to be attached thereto. This is especially desirable in the case of such shoes 40 as bluchers in which the quarter is attached to that side of the vamp which will be on the outside when the shoe is assembled. The proper overlap for the quarters may be indicated on a vamp either alone or in combination 45 with one or more other marks such as the toe tip overlap, or the box toe overlap and either at the same time or different times therefrom. Preferably, however, the overlap for the quarters will be indicated on 50 the vamp simultaneously with the other marks it is desired to indicate thereon.

In the machine herein described, the means for marking on the vamp the proper overlap for quarters to be attached thereto 55 is shown as movable in unison with the

vamp supporting and positioning means in its adjustment for right and left vamps, and a third feature of the invention relates to the provision of means for supporting and maintaining a vamp in correct position to 60 be marked, which means are adjustable relative to certain stationary marking agencies to adapt the machine to mark differently on right and left vamps, in combination with other agencies which are movable in unison 65 with said supporting and maintaining means relative to said stationary marking agencies for marking on the vamp certain points of constant position irrespective of such right and left adjustment. 70

Referring to the accompanying drawings, Figure 1 is a plan view, partly broken away, of a vamp marking machine having my invention applied thereto; and Fig. 2 is a perspective view of a detail thereof. 75

The specific form of vamp marking machine to which I have shown my invention as applied is that shown in the co-pending application of C. H. Bayley, Serial No. 312,218, filed April 17, 1906 and comprises 80 a base A which may be given a skeleton form, a marking bed B preferably formed of some relatively soft material such as wood or rubber to avoid injury to the marking agencies, a vamp supporting table C, 85 and a marker carriage D.

The vamp supporting table C is secured to the base A preferably by means of a pivot bolt 2 and is mounted to swing laterally of said base between limits which may 90 be adjusted by screw 4, as shown in said application. Table C is provided with two slots 6 and 8 in which move the pairs of pins 10 and 12 respectively, adjustable toward and from each other by milled headed 95 screws 14 and 16 respectively. These pins engage the vamp positioning and marking members 20, hereinafter to be more particularly described, and are adjustable to adapt said members 20 to fit any size or 100 style of vamp through milled headed screws 14 and 16 and locking device 18, as shown in said pending application.

The means for marking a vamp supported on the table are substantially the same as 105 shown and described in said co-pending application and comprise a marker 22 for indicating a line extending longitudinally through the middle of the instep portion of the vamp, a marking point 24 for marking 110

the vamp at a point substantially above the axis of pivot bolt 2 to indicate the center of the vamp throat, a tip marker 26 and a box toe marker 28 for indicating the line of overlap of the toe tip and box toe respectively. Markers 26 and 28 are adjustably held on the outer ends of bent arms 30 which are pivoted to the striking lever 32 and have interengaging toothed sectors 34. The striking lever 32 is provided with a segmental bar 38 for supporting the striking ends of bent arms 30 and may have a knob 36 by which it may be depressed, being returned to elevated position by a coiled spring 40. Markers 22 and 24 are supported on a bracket 42 which is depressed by striking lever 32. Markers 26 and 28 are mounted on carriage D which may be moved lengthwise of the machine on rails 44 by eccentric cam 46 to provide a ready adjustment for different styles of toe tips or box toes independent of the different sizes or styles of vamps, while to provide for successive adjustments of the tip or box toe markers to suit different sizes and styles of vamps the machine has a shifting lever 48 pivotally connected to its base A and carrying adjustable slide 49 to adjust the point of connection therewith of a link 50 which is also connected to the rear cross bar of the carriage D.

Vamp positioning and marking means 20 comprises a pair of flat plates each having openings to receive one of each of the pairs of pins 10 and 12. As the distance between said pins varies with their adjustment to suit different styles of vamps, one of the pins passes through a slot formed in said plate *a* while the other fits rather closely in its socket. Plate *a* has pivotally attached thereto at its rear end a marker arm *b* carrying marker pin *d* preferably through an intermediate carrier member *c*, to provide for adjustment. Member *c* is shown as forked to receive the end of arm *b* but has two clamping screws *e* and *f* passing respectively through enlarged and elongated slots formed in said arm. These provide for adjustment of the marker points both lengthwise of the machine and also transverse thereof, while any convenient means may be provided for adjusting said points vertically to adapt them to make a deep or shallow indentation, for instance a screw and jam nut *g* fitting on the upper end of the pin *d*. To provide for properly positioning the vamp on the bed, a pin *h* may be screwed into an opening formed in plate *a* and other openings *i* may be provided to receive said pin corresponding to different lengths of vamps. A spring *k* may be provided for holding the marker arm *b* elevated.

In operation the vamp indicated in broken lines on Fig. 1 is supported on table C and

marking bed B, the correct position being determined by means of pins *h* which fit in the recesses flanking each side of the throat. By turning the milled headed screws 14 and 16 either together or separately the position of pins *h* may be changed to fit the throat of any size or style of vamp. To accommodate vamps of widely different length, pins *h* may be adjusted from one hole *i* to another and by turning table C on its pivot 2 the machine may be adjusted to accommodate right and left vamps. The vamp being supported in proper position on its bed and the marking devices properly adjusted thereabove the operator depresses striking lever 32 through its actuating means. This operates to indicate on the vamp the various marks as described in the application of Bayley above referred to, should it be desired to have all these points indicated on the vamp.

In practice the agencies for indicating the middle line of the instep and the center of the throat would be removed from the machine or rendered inoperative in the manner disclosed in the said application of Bayley when it was desired to mark blucher vamps. The depression of striking lever 32 also serves to indicate on the vamp the proper overlap for the quarters which is especially desirable in the case of blucher vamps. This last operation is accomplished through the medium of segmental bar 38, which, as striking lever 32 is depressed, strikes the carrier for marking pin *d*, causing said pin *d* to indicate the desired point on the vamp.

It should be noted that the relationship of each marking pin *d* to its corresponding vamp positioning pin *h* remains constant irrespective of the angular movement of the vamp supporting table and pins *h* to accommodate right and left vamps and that consequently said pins *d* indicate points on the vamp which are stationary and independent of such adjustment.

Having described my invention, what I claim as new and desire to secure by Letters Patent of the United States is:—

1. In a vamp marking machine, the combination of angularly adjustable means for supporting a vamp in position to be marked, and means for indicating on a vamp so supported the proper overlap for quarters to be attached thereto.

2. In a vamp marking machine, the combination with angularly adjustable means for supporting a vamp in position to be marked, of means for indicating thereon the proper overlap of the toe tip, and means for indicating thereon the proper overlap for quarters to be attached thereto.

3. In a vamp marking machine, the combination of means for supporting a vamp in position to be marked, and means for indi-

cating on a vamp so supported the proper overlap for quarters to be attached thereto, said supporting and indicating means being adjustable relative to each other to accommodate right and left vamps.

4. In a vamp marking machine, the combination of means for supporting a vamp in position to be marked, and means for indicating on a vamp so supported the proper overlap for quarters to be attached thereto, said supporting and indicating means being adjustable relative to each other between predetermined limits to accommodate right and left vamps.

15 5. In a vamp marking machine, the combination of means for supporting a vamp in position to be marked, means for indicating on a vamp so supported the proper overlap for quarters to be attached thereto, said supporting and indicating means being adjustable relative to each other between predetermined limits to accommodate right and left vamps, and means for adjusting said limits.

25 6. In a vamp marking machine, the combination of means for supporting a vamp, detachable means for insuring the correct position of a vamp so supported, and means for indicating on a vamp so supported the proper overlap for quarters to be attached thereto.

35 7. In a vamp marking machine, the combination of means for supporting a vamp, pins adapted to each engage one of the recesses flanking the throat of said vamp for insuring the correct position of said vamp, and means for indicating on a vamp so positioned the proper overlap for the quarters to be attached thereto.

40 8. In a vamp marking machine, the combination of means for supporting a vamp, pins each engaging one of the recesses flanking the throat of said vamp to insure the correct position thereof, said supporting means being provided with means for permitting adjustment of said pins to accommodate vamps of different length, and means for marking on a vamp so supported the proper overlap for quarters to be attached thereto.

50 9. In a vamp marking machine, the combination of means for supporting a vamp, pins each engaging one of the recesses flanking the throat of said vamp to insure the correct position thereof, means for marking on a vamp so supported, means for moving said supporting and positioning means and marking means relative to each other to adjust the machine to mark on right and left vamps, and means for indicating on a vamp so supported a plurality of points of constant position independent of such right and left adjustment.

10. In a vamp marking machine, the combination of means for supporting a vamp, 65 pins carried thereby and each engaging one of the recesses flanking the throat of said vamp to insure the correct position thereof, means for marking on a vamp so supported, means for adjusting said supporting and 70 positioning means to adapt the machine to mark on right and left vamps, and means for indicating on a vamp so supported a point of constant position relative to one of said positioning pins and independent of 75 such right and left adjustment.

11. In a vamp marking machine, the combination of vamp supporting and positioning means adjustable to accommodate right and left vamps, means for providing a vamp 80 supported thereby with marks, the positions of which vary with such right and left adjustment, and means for providing a vamp so supported with marks whose position does not vary with such adjustment. 85

12. In a vamp marking machine, the combination of vamp supporting and positioning means adapted to be adjusted for right and left vamps, and marking means adjustable in conformity with the adjustment 90 of said first mentioned means.

13. In a vamp marking machine, the combination of vamp supporting and positioning means adapted to be adjusted for right and left vamps, and marking means adjustable in unison with said first mentioned means. 95

14. In a machine of the class described, the combination of means for supporting the vamp, means for indicating the line of attachment to the toe tip, said supporting means being adjustable to accommodate right and left vamps, and means for making a plurality of marks whose position on said vamp is independent of said adjustment. 100 105

15. A vamp marking machine having, in combination, marking devices for indicating the line of attachment of the tip, a vamp supporting table, a plurality of positioning plates on said table, and marking devices for 110 indicating the overlap of the quarters carried by said plates.

16. A vamp marking machine having, in combination, means for indicating the line of attachment of the tip, a supporting table, 115 means for indicating the overlap of the quarters and means whereby said last named means may be adjusted to vary the extent of the overlap.

In testimony whereof I have signed my 120 name to this specification in the presence of two subscribing witnesses.
